UNITED STATES PATENT OFFICE.

JOSEPH GOSSNER, OF NEW YORK, N. Y.

DESIGN FOR A COMBINED PAPER WEIGHT, CIGAR CUTTER, AND FLAG STAND.

61,339.

Specification for Design.

Patented Aug. 8, 1922.

Application filed February 15, 1922. Serial No. 705. Term of patent 7 years.

To all whom it may concern:

Be it known that I, JOSEPH GOSSNER, a citizen of the United States, residing at New York, county and State of New York, have invented a new, original, and ornamental Design for a Combined Paper Weight, Cigar Cutter, and Flag Stand, of which the following is a specification.

The drawing shows the combined paper-weight, cigar-cutter, and flag-stand in ele-

vation. The column containing the cigar-cutter and supporting the flag-pole is cylindrical as shown.

I claim as my invention:

The ornamental design for a combined paper-weight, cigar-cutter, and flag-stand as shown.

In testimony whereof I affix my signature.

JOSEPH GOSSNER.
